FILLING REPLENISHING MECHANISM FOR DOUBLE SHUTTLE LOOMS

Application filed February 10, 1932. Serial No. 591,988.

This invention relates to filling replenishing looms, and more particularly to filling replenishing looms weaving with two shuttles.

Looms weaving with two shuttles may be utilized for the production of various fabric constructions. Where two sheds are formed by the warp threads and the shuttles are picked, each through one of the sheds, two superposed webs result, and when such superposed webs are united by pile forming threads a double pile fabric is produced which, when the two webs are cut apart by severing the pile forming threads uniting them, two pile fabrics are formed. In the production of the described fabrics the shuttles are usually picked simultaneously each through its own shed.

In other instances where the loom is weaving with two shuttles picked through the same shed alternately, a single fabric is formed. In all these cases it is the usual practice to provide the two shuttles with substantially the same amount of filling. Should the loom be of the filling replenishing type, it has been the common practice to effect replenishment of each shuttle separately when the filling in that shuttle has become substantially exhausted. This has resulted in repeated operations of the replenishing mechanism, and when the loom is of the type that suspends or slows up the loom operation during replenishment, much loss of time and product result.

The invention will be exploited and described as embodied in a loom for weaving double pile fabrics but it is to be understood that the invention is not limited in this respect and may be advantageously employed in connection with other types of looms weaving with two shuttles.

The novel features of the invention and associated controls and safety appliances will best be made clear from the following description and accompanying drawings of one good form thereof.

In the drawings:—

Fig. 1 is a front perspective view of a double pile fabric loom containing the present invention, some of the parts being omitted for clearness of illustration;

Fig. 2 is a side elevation at the replenishing side of the loom, some of the details being shown in section or broken away, and the loom at rest;

Fig. 3 is a side elevation at the non-replenishing side of the loom;

Fig. 4 is an enlarged sectional elevation showing portions of the lay, replenishing shuttle boxes, the two magazines or hoppers, and the shuttle carriers in their first position on call for replenishment of filling;

Fig. 5 is a sectional side elevation of a protector mechanism and safety device;

Fig. 6 is a detached detail of the change shaft control;

Fig. 7 is an enlarged perspective view at the non-replenishing side of the loom, some of the parts being omitted and others shown broken away for clearness of illustration;

Fig. 8 is an enlarged detached side elevation of the filling fork control; and

Fig. 9 is a detail in side elevation of details pertaining to the loom stopping and replenishing control.

The loom shown is of the double pile fabric type using two shuttles which may be simultaneously picked through two sheds for the production of two superposed webs which are united during the weaving operation by pile forming warp threads, and the general means for this purpose may be as usual.

The loom frame 1 may be of any suitable construction for support of the operating parts and such parts may be actuated from any suitable source of power. In the present instance the power driving means consists of an electric motor 2 supported at the rear of the loom and having gearing connections 3 and 4 for driving the back shaft 5. Mounted above the shaft 5 is the rock shaft 6, the downwardly extending arms 7 of which engage in the circular recess of a clutch member mounted for sliding movement on the shaft 5 whereby the clutch members may be engaged or disengaged at desired times. Connected to the back shaft 5 is a gear 8 which meshes with the pinion 9 to actuate the crank shaft 10 when the clutch members are engaged. The crank

shaft is connected to the lay swords 11, Fig. 3, by the usual pitman 12 whereby the lay 13 may be given its beatup movements, as usual. The train of mechanism for actuating other going parts of the loom are not herein illustrated because the details thereof of form no essential part of the present invention and are now well understood in the art.

10 Extending transversely of the loom frame is the shipper shaft 14 to which is secured the shipper 15 shown in Fig. 3 in full lines in its running position, and extending downwardly from the shipper shaft is the arm 16 connected by the rod 17 to the clutch control member such as the slide 18 for actuating the arm 19 and shaft 6 to manipulate the clutch, the construction being such that when the shipper 15 is in its full line position, Fig. 3, 15 the clutch members are engaged and the loom is in running position.

The shedding mechanism for manipulating the warp threads α in the formation of the two sheds may be as usual, but as herein shown consists of a series of harness frames 20 for controlling the warp threads in their rising and falling movements, as usual. The lay 13 carries a reed 21 through which the warp threads pass on their way to the fell of the cloth, and the two sheds in connection with the filling threads, as usual, serve to produce the two superposed webs while the pile forming warps manipulated by a suitable shedding mechanism pass back and forth between the two webs for the production of a double pile fabric, as indicated in Fig. 1. As the double pile fabric is fed forward the pile forming threads are cut and as shown the cutting mechanism may consist of a carriage 22 having a knife and operated transversely back and forth by suitable actuating means, now well known in the art, with the result that the two superposed webs are cut apart and produce the two separate pile fabrics 23 and 24 which are led about suitable spike or sand rolls 25 and 26, and driven synchronously through the gears 27 to take up the two pile fabrics which are led to suitable cloth rolls. The mechanism thus far described is now well known and needs no further elucidation.

The lay 13 is provided with the shuttle replenishing boxes at one side of the loom and the non-replenishing boxes at the opposite side and during the weaving operation the picker sticks 28 act upon both shuttles to pick each through its respective shed, and inasmuch as the upper shuttle of the two travels for the most part upon the lower plane of the upper shed of warp threads a short shuttle guide 29 extends from the inner end of the upper shuttle box to direct the shuttle, as indicated in Fig. 1. It may be desirable in some cases to provide an upper guide for the upper shuttle to insure its accurate picking

movement and this is provided in the present instance by the shoes or guides 30, Fig. 1.

The loom illustrated is of the shuttle changing type and an important feature of the present invention resides in making a double shuttle change when either shuttle indicates substantial exhaustion of filling.

Rising from the lower portion of the loom frame at the replenishing side is a hopper support 31 for sustaining the two full shuttle supply hoppers or magazines. In the present instance the hopper support 31 is provided with the supporting lugs 32 which may be adjustably secured to the hopper support 31 by the bolts 33. Each of the lugs 32 has extending therefrom a supporting arm 34 which is engaged with suitable projections 35 extending from the hoppers or magazines 36, Figs. 1 and 2, and in order that the hoppers may be held in fixed position they are connected to the supporting arms adjustably by suitable clamps or set screws 37, Fig. 2.

Each of the hoppers 36 will ordinarily contain a series of shuttles 38 supplied with filling and ready to be transferred from the hoppers to the shuttle boxes on call for replenishment of filling.

In order that the shuttles in each of the hoppers may be retained therein each hopper is provided with a stop or abutment on which the lower shuttle rests during normal weaving operations. Such abutment or stop may consist of arms 39 pivotally mounted at 40 to the hopper wall and each having a downwardly extending tail portion 41 and a rearwardly extending lug 42 on which the lower shuttle of the series may normally rest, Fig. 2.

Since, in accordance with the present invention, two shuttles are to be simultaneously transferred from the hoppers to the shuttle boxes, the hoppers themselves are arranged in staggered relation, that is, one hopper is frontward of the other while the other is higher than the front one, as clearly illustrated in Figs. 2 and 4. This arrangement of the hoppers likewise enables the shuttle carriers, to be hereinafter described, to move in their respective different paths in transferring a shuttle from the hoppers to the two shuttle boxes which, as will be observed, are one above the other.

The two shuttle carriers for transferring a shuttle from each of the hoppers to the respective shuttle boxes consist of the arms 43 and 44 which are pivotally mounted at their lower ends at 45, Fig. 2, and each has a projecting cam engaging member 46, 47 which normally take the position indicated in Fig. 2 during normal weaving operations and when the loom is at rest.

The upper portion of each of the carriers 43, 44 is provided with a shuttle supporting portion 48 on to which a shuttle from the hoppers will drop when the abutments 42 of the hoppers are withdrawn.

To withdraw the abutments or projections 42 and thus permit a shuttle to drop from each hopper on to the support 48 the shuttle carriers 43, 44 are first given a forward movement to a slight extent sufficient to cause the tail portion 41 of the abutment 42 to be engaged by the upper end of the carriers and be moved outwardly, as indicated in Fig. 4, whereupon a shuttle from each hopper will drop on to the supports 48.

It may be desirable in some instances to obstruct the downward movement of the shuttles above those which have been dropped until the abutments 42 can again assume their initial position. This condition is portrayed in Fig. 1 wherein it will be noted that the pivotal support 40 of each abutment comprises a rock shaft normally under the influence of a spring 49, Fig. 1, tending to move the abutment inwardly to its normal position, and pivotally mounted upon the hoppers at 50 is a stop finger 51 which is connected to a crank arm on the shaft 40 by a pin 52, such that as the abutment swings outwardly into the position of Fig. 4 the stop fingers will be turned inwardly to hold the stacks of shuttles from dropping downwardly in the hoppers.

In order that shuttles may be transferred simultaneously from both hoppers to the two shuttle boxes, the two running shuttles must be first discharged from the boxes, as indicated in Fig. 4. Rising from the lay 13 is a bracket or arm 53, of which there may be two, separated longitudinally of the lay a suitable distance apart, and pivotally mounted at the upper end portion of the bracket 53 is a rock shaft 54 on which is mounted the front box plate actuating arms 55. The front box plate 56 is pivotally connected at its upper end at 57 to the arms 55 and such pivotal connection may take the form of a rock shaft, as clearly indicated in Fig. 1, the construction being such that if the arms 55 are moved upwardly into the position indicated in Fig. 4 the front box plate will likewise be lifted to free the front of the shuttle boxes for the ejection of the running shuttles.

The front box plate 56 has an upwardly extending arm 58 to which is connected a link 59, its opposite end being connected at 60 to a fixed lug 61, the construction being such that as the front box plate is turned upwardly to permit the ejection of the running shuttles it will rise in a substantially vertical direction under the dictates of the parallel link motion and consequently will not be thrown outwardly from the shuttle boxes an undue amount which might interfere with other working loom parts and the front box plate will take position, as indicated in Fig. 4 with the front of the shuttle boxes open for the ejection of the running shuttles.

In order to eject the two running shuttles the present invention provides duplicate

70 kickers 62 which are carried by one or more arms 63 pivotally mounted at 64 and having an upwardly extending member 65, Fig. 4. The end portion of the arm 65 is provided with a kicker operating member 66 which may preferably take the form of an adjusting screw, Fig. 2, the lower end of which will be struck by the upper portion 67 of the front box plate as the latter is swung upwardly in its parallel link movement and approaches its upward limits to expose the front of the shuttle boxes for the ejection of the running shuttles. The running shuttles having been ejected under the conditions shown in Fig. 4, the kickers are caused to be withdrawn from the shuttle boxes by a withdrawing member 68, Fig. 4, the end portion 69 of which engages frontwardly of the arm 63 and moves it to withdraw the kickers on the initial movement of the front shuttle box wall to its initial position.

80 As will be apparent from Fig. 4, the front box plate 56 is given an amount of upward movement somewhat in excess of that required to uncover or free the shuttles to be ejected and such excess of movement is utilized to operate the kickers, so that as the front box plate approaches the upper limit of its movement, the upper portion 67 of the front box plate will strike the kicker operating member 66, the lower end of which is normally some distance above the upper portion 67 of the front box plate, and so cause the shuttles to be ejected. Before the incoming shuttles are transferred to the shuttle boxes, the front box plate 56 starts downward towards its initial position, whereupon the withdrawing member 68 withdraws the kickers from the shuttle boxes during the first part of the front box plate movement and before the front box plate is sufficiently lowered to obstruct the entrance of the fresh shuttles to the shuttle boxes. The kickers are thus removed from the shuttle boxes, the fresh shuttles are transferred to the shuttle boxes, and then the front box plate completes its movement to initial position.

100 Extending from the rock shaft 54 carried by the brackets 53 is an arm 70 connected by a link 71 to the lower arm 72 supported by the rock shaft 73 at the lower part of the brackets 53, and connected with the arm 72 is a spring 74 which normally acts to move the front wall of the shuttle box back to its initial position after having been displaced.

110 In the construction thus far described it will be apparent that upon the actuation of the shuttle replenishing mechanism hereinbefore described, the two running shuttles will be replaced by shuttles supplied with filling, and inasmuch as the loom shown is of the general type wherein weaving operations are suspended during a change of shuttles it becomes appropriate at this time to

point out how the indication of filling exhaustion in either of the shuttles brings about a change in both shuttles.

Opposite the shuttle boxes on the non-replenishing side of the loom is a feeler mechanism which serves to detect the condition of the filling in each shuttle while in the non-replenishing boxes, and while suitable form of feeler mechanism may be employed to detect substantial exhaustion of filling in either shuttle, the feeler mechanism shown consists of two pair of feeler members 75, one pair cooperating with each shuttle. The feeler mechanism shown is of the electric type and when the filling in either shuttle has reached a predetermined degree of exhaustion the metal collars 76 on the cooperating feeler members will engage a metal plate 77 on the substantially depleted shuttle and close an electric circuit 78, Fig. 1, thereby energizing a solenoid or magnet 79. Connected to the core of the solenoid is a rod 80 normally under the stress of a light spring 81 and having a sliding member 82, the end of which normally extends across the guide 83 and under a wire or arm 84 which is itself connected to the actuator 85, the construction being such that during normal weaving operations the end portion 86 of the actuator will be held in a raised position out of the path of the shouldered portion 87 of the cam follower 88. When, however, the solenoid is energized or excited by the closed circuit through either pair of feelers the rod 80 will be drawn to the right, Figs. 1 and 7, thereby withdrawing the end of the slide 82 from under the arm 84 and permitting the end portion 86 of the actuator 85 to drop into the path of the shouldered portion 87 of the cam follower 88.

The actuator 85 is pivotally connected at 89 on a bell crank lever 90 pivotally mounted upon a support 91. The arm 91 of the bell crank lever carries a clamp 92, downwardly from which extends the replenishing control rod 93, the lower end portion of which is connected at 94, Fig. 3, to a lever 95 pivotally supported at 96 on the loom frame.

Mounted for continuous movement on the shaft 5, Fig. 3, is the beveled gear 97 which meshes with a beveled gear 98 secured to the upper end portion of the transmitting shaft 99, on the lower end of which is a worm 100 which is in continual connection with the worm wheel 101, Fig. 6. The worm wheel 101 is fixed to a sleeve 102 loosely mounted upon the change shaft 103, the construction being such that while the worm wheel and sleeve 102 may rotate continuously the shaft 103 remains idle during normal weaving operations.

Keyed to the shaft 103 is a disk member 104 and mounted on the sleeve 102 is an

adjacent disk member 105 which is provided with a series of openings or holes 106, Fig. 3, any one of which is adapted to be engaged at times by a pin 107 mounted upon the radial arm 108 which, as usual, is normally held in position with the pin 107 withdrawn from a notch 106 in the disk 105 by a controller 109, Fig. 6. So long as the controller 109 is prevented from movement about its pivotal support 110 it bears upon the radial arm 108 and holds the pin disengaged from the notch in the disk 105.

Pivotedly mounted at 111 is an angular latch member 112, Figs. 3 and 6, the upper end portion of which normally overlies the arm 113 on the controller 109, with the result that so long as the parts are in the position indicated in Fig. 6 the radial arm 108 holds the locking pin 107 from engagement with a notch in the disk 105.

Connected to the lever 95 previously described, Fig. 3, is a link member 114 normally under the influence of a spring 115 and connected to the arm 116 of the latch 112, with the result that during normal weaving operations the parts maintain the position indicated in Figs. 3 and 6, but on call for replenishment of filling through the actuator 85, as described, the lever 95 throws the upper end of the latch 112 from engagement with the controller 109 whereupon the shaft 103 becomes locked for rotative movement with the sleeve 102. The movement of the lever 95 is sudden and just sufficient to free the latch 109 and permit the end of the radial arm 108 to pass beyond the end of the lower end of the latch, whereupon the parts again assume their locked position, as indicated in Figs. 3 and 6, so that on a single rotation of the change shaft 103 the locking pin 107 is again detached from the engaged notch and the change shaft comes to rest.

Mounted on the change shaft 103 are the controlling cams, one 117, for raising the front wall of the shuttle boxes and the other two, 118 and 119, for controlling the movements of the shuttle carriers 43 and 44, Fig. 2.

Mounted on shaft 73 carried by the lay is an arm 120, Figs. 2 and 4, the end portion of which is connected to a downwardly extending rod 121 which at its lower end is jointed to a lever 122 pivotally supported at 123 on the loom frame, and cooperating with the lever 122 is the cam 117, previously mentioned, which acts upon a roll 124 carried by the lever 122, the effect being that on starting the change shaft 103, as hereinbefore described, the cam 117 will serve through the described connections to raise the front wall of the shuttle boxes from the position indicated in Fig. 2 to that shown in Fig. 4, whereupon the running shuttles are discharged from their boxes, as already described.

As previously mentioned, the shuttle carriers 43, 44 are each given a slight frontward

130

movement at their upper ends to permit a shuttle from each of the hoppers or magazines to pass into control of the carriers, a condition that is brought about by a slight 5 hump 125, 126 formed as part of the shuttle carrier operating cams 118, 119, Fig. 2. As the change shaft continues to rotate after having given the forward movement to the shuttle carriers the rolls on the ends of the 10 arms 46, and 47 of the carriers pass along the contour of the cam, or rather the cams pass under the rolls permitting the latter to ride into the lower portion of the cams, whereupon the springs 127 and 128, which are connected to the shuttle carriers 43 and 44, move the latter backwardly in their respective different paths to substitute a full shuttle in each of the shuttle boxes to replace the previously ejected shuttles, as indicated in Fig. 15 20 4, whereupon the rising portions of the two cams 118, 119 return the carriers to their forward position, as indicated in Fig. 2 and at this time the double shuttle replenishment has been completed.

25 The double pile fabric loom, shown in the drawings, is of the type where the loom operation is interrupted or the loom brought to rest during the replenishing cycle of the loom and since loom stoppage must be effected at 30 or about the time that replenishment is called the present invention provides means for stopping the loom on call for replenishment of filling, as follows, having reference more particularly to Figs. 3, 7 and 9.

35 The bell crank lever 90, to which the actuator 85 is pivoted, has a pin 129 which bears upon the lower arm 130, Fig. 9, of the lever 131 pivotally supported on the same pivotal mounting as is the bell crank lever 90, Fig. 9, 40 and connected to the lower arm 130 of the lever is a link 132, the outer end portion of which is provided with a slot 133, which is engaged by a pin 134 extending from an arm 135 secured to the shipper shaft 14, the pin 45 134 normally resting at the end of the slot, as indicated in Fig. 9, the result being that when the actuator 85 is moved forwardly on call for replenishment of filling the pin 129 will turn the lever arm 130 to the right, Fig. 9, thereby turning the shipper shaft and the shipper 15 to loom stopping position. The slot 133 in the link 132 permits movement of the shipper to its stopping position by hand if desired.

50 On call for replenishment of filling and from the mechanism hereinbefore described it will be apparent that the loom will be stopped and the change shaft 103 be turned for one complete revolution, thereby effecting replenishment in both shuttle boxes, and prior to the completion of the single revolution of the change shaft the loom is to be automatically restarted.

55 Mounted for rocking movement about the centre 123 is the starting arm 136, Figs. 2 and

5, to which is rigidly secured for movement therewith an arm 137, the end portion of which is in the path of movement of a trip cam 138 which, just prior to completion of a single revolution of the change shaft 103 70 rides under the arm 137 and moves the starting arm 136 to the left, Fig. 2.

Passing loosely through the upper end of the starting arm 136 is the starting rod 139 having a slotted member 140 which is provided with a locking notch 141 normally engaged by a pin 142 extending from the arm 143 mounted for limited rocking movement on the shipper shaft 14, Fig. 5. The arm 143 is connected to the lower portion of the shipper lever 15 by a pin and slot connection 144 and a spring 145 extends between the auxiliary handle 146 and the arm 143 thereby permitting a limited yielding movement as a factor of safety.

80 A spring 147 surrounds the starting rod 139 between a fixed collar 148 and a loose collar 149 against which bears the starting arm 136, with the result that when the starting arm 136 is moved to the left, Fig. 2, it 90 acts upon the nut or abutment 150 to draw the starting rod 139 to the left and therefore move the shipper 15 to its loom operating position as the cam 138 passes under the arm 137. When the cam has finally passed the 95 arm 137 into the normal loom running position, as indicated by dotted lines in Fig. 2, the starting arm 136 will be moved about its pivotal support in the opposite direction or to the right, Fig. 2, under the impulse of the spring 127 which connects it with the shuttle carrier 43. At this time the arm 136 will slightly compress the spring 147 and the end of the starting rod 139 will project beyond the end of the starting arm, as indicated by 100 dotted lines, Fig. 5, and the loom will then be started.

105 It may happen at times that one of the shuttles will fail to be properly positioned in its box and if filling replenishment were called at this time a smash would occur, and so the present invention provides a safety device or protector mechanism, so that after the loom has been stopped by a mis-positioned shuttle it cannot be again automatically started.

110 Mounted upon suitable ways on the machine frame is a sliding frog 151 which may be actuated or pushed forwardly by either of the dagger fingers 152 and 153, Fig. 5, to 115 thereby effect loom stoppage.

120 In the present instance the frog 151 has a stop finger 154 extending forwardly therefrom and normally bearing upon the lower end portion of the shipper 15 or its associated arm 143 while the loom is running. The frog is held retracted by a spring 155 and when moved forwardly by one of the daggers 152 and 153 the end of the frog abuts against a rubber bumper 156 to check the 130

frontwardly movement of the frog in conjunction with the spring 155.

Each of the daggers 152 and 153 is pivotally supported upon the lay, as usual, and extending upwardly therefrom are fingers 157 and 158, which bear against the usual binders of the shuttles boxes, with the result that should a shuttle not be properly boxed the associated dagger will drop and engage one of the shoulders carried by the frog 151 and cause the frog to slide frontwardly and thereby effect loom stoppage.

Pivottally mounted on the loom frame at 159 is an arm 160 having a pin 161 which bears upon the lower side of the starting rod 139. The upper end of the lever 160 is connected at 162 to a link 163 pivotally jointed to the frog 151 at 164, the result being that when the frog is moved frontwardly by reason of an improperly boxed shuttle it will first cause the shipper to move to its loom stopping position and will simultaneously turn the lever 160 to thereby lift the starting rod and detach the notch 141 from the pin 142 of the starting lever, with the result that even should filling replenishment have been called the starting arm 136 cannot move the shipper to its loom running position.

Upon failure of filling to be laid in the shed by either shuttle, the present invention proposes that the loom be stopped for correction of the filling fault and that the replenishing mechanism be rendered inoperative so that even should replenishment be called 35 when the filling fails the loom will be stopped without initiation of the replenishing operation and as one form of means to carry out the intended purpose of the invention there is a filling fork mechanism at the non-replenishing side of the loom which detects presence or absence of filling from either shuttle on detecting beats.

Mounted in close proximity to the cam follower 88 is a filling fork carrier 165, Fig. 8, comprising an arm pivotally supported at its lower end at 166 and secured to the filling fork carrier are the stands 167 and 168, each of which has pivotally mounted thereon a filling fork 169 and 170, the frontwardly extending ends of which are provided with hooks 171 and 172.

Mounted on the cam follower 88, Fig. 8, are the follower hooks 173, 174, pivotally connected to the cam follower at 175 and 176. The forward end portions of the hook members 173 and 174 carry a lifter 177 which is provided with a frontwardly extending portion 178 normally located slightly below the end 86 of the actuator 85. Should either filling fork detect absence of filling laid in the shed its front hook portion will engage the associated hook member on the cam follower, as indicated by dotted lines on the lower filling fork, Fig. 8, with the result that 60 the lifter 177 will be raised, and its project-

ing portion 178 will lift the rear end portion of the actuator 85 above the path of the shouldered portion 87 of the cam follower and perforce thereby lift the actuator so that it cannot be moved by the cam follower even should filling replenishment be called at this time.

To effect loom stoppage under the above conditions the filling fork carrier 165 has connected to its upper end at 179 a rod 180 which extends frontwardly, Figs. 8 and 9, and connects with the upper end of the lever arm 131, with the result that on frontward movement of the cam follower the link 132 which, as before described as connected with the shipper 15, Fig. 9, will throw the shipper from its running to its stopping position.

The double shuttle change, as shown in Fig. 1, is about completing the transfer of a shuttle from each of the shuttle magazines or hoppers to the two shuttle boxes, and it will be noted that the two shuttle carriers 43, 44 are in substantially their back position with the shuttle supporting portions 48 extending into each of the shuttle boxes and the front wall of both shuttle boxes, which is formed in one piece, is in its raised or substantially raised position.

As the shuttle carriers 43 and 44 are withdrawn from the shuttle boxes, the front wall of the shuttle boxes which is formed as a single member, should obstruct the withdrawal of the newly supplied shuttles from the shuttle boxes and as a convenient means to this end the front wall 56 is provided with openings 181 which permit the front wall of the shuttle boxes to descend to substantially its lower position as the shuttle carriers 43 and 44 are withdrawn.

The loom frame has mounted thereon a shuttle receiver 182, Figs. 1 and 2, for the reception of the discarded shuttles as they are ejected from the shuttle boxes and in order to guide the shuttles downwardly into the receiver it is appropriate that a guide or apron 183 be employed.

From the construction described as one good form or embodiment of the invention it will be apparent that upon detection of substantial exhaustion in either shuttle by the feeler mechanism both of the running shuttles will be replenished, the old or running shuttles will be ejected from the two shuttle boxes and two shuttles supplied with filling will be transferred to the two shuttle boxes.

What is claimed is:—

1. In a filling replenishing loom of the shuttle changing type weaving with two shuttles, the combination of the lay and shuttle boxes, filling detecting mechanism for detecting the condition of the filling in both shuttles, and shuttle changing mechanism rendered operative on detection of a filling fault in either shuttle for changing the shuttles in both boxes at the same time.

2. In a shuttle changing loom weaving with two shuttles, the combination of the lay having two shuttle boxes at the same side of the loom, detector mechanism for detecting the condition of the filling in both shuttles, and shuttle changing mechanism rendered operative on detection of substantial exhaustion of filling in either shuttle to change both shuttles at the same time. 70
- 10 3. In a shuttle changing loom weaving with two shuttles, the combination of the lay having two shuttle boxes at the same side of the loom, detector mechanism at the opposite side of the loom for detecting the condition of the filling in both shuttles, and shuttle changing mechanism rendered operative on detection of substantial exhaustion of filling in either shuttle to change both shuttles at the same time. 75
- 15 4. In a shuttle changing loom weaving with two shuttles, the combination of the lay, two shuttle boxes at each side of the loom, shuttle changing mechanism at one side of the loom, detector mechanism for detecting the condition of the filling in both shuttles, and means rendered effective on detection of substantial filling exhaustion in either shuttle for causing the shuttle changing mechanism to become operative to change both shuttles. 80
- 20 5. In a filling replenishing loom weaving with two shuttles, the combination of the lay and shuttle boxes, detector mechanism for detecting the condition of the filling in the shuttles on detecting beats, and filling replenishing mechanism rendered operative on detection of substantial exhaustion of filling in either shuttle for simultaneously replenishing the filling in both boxes as a result of such single detection. 85
- 25 6. In a shuttle changing loom weaving with two shuttles, the combination of the lay provided with two shuttle boxes at the same side of the loom, shuttle changing mechanism for changing the shuttles in both boxes on one operation of the shuttle changing mechanism, and means for operating the shuttle changing mechanism to change both shuttles when either of them indicates substantial exhaustion of filling. 90
- 30 7. In a shuttle changing mechanism for looms, the combination of the lay provided with two shuttle boxes at one side of the loom for weaving with two shuttles filling detecting mechanism for detecting the condition of the filling in both shuttles, a shuttle changing mechanism for each shuttle box, and means rendered operative on detection of substantial exhaustion of filling in either shuttle for operating both shuttle changing mechanisms to eject simultaneously the two running shuttles from their respective shuttle boxes and insert a full shuttle for each at the same time. 95
- 35 8. In a shuttle changing loom, the combination of the lay provided with two shuttle boxes at the same side of the loom for weaving with two shuttles, shedding mechanism for dividing the warp threads into two sheds, one for each shuttle, shuttle changing mechanism for changing the two shuttles together, and means rendered operative on substantial exhaustion of filling in either shuttle for ejecting together the two running shuttles and inserting two full shuttles. 100
- 40 9. In a shuttle changing loom, the combination of the lay having two shuttle boxes at each side of the loom for weaving with two shuttles, shedding mechanism for dividing the warp threads into two sheds, one for each shuttle, filling feeler mechanism for detecting the condition of the filling in both shuttles, shuttle changing mechanism for changing the shuttles in both boxes on a single operation of the shuttle changing mechanism, and means rendered operative on detection of substantial exhaustion of filling in either shuttle for causing the shuttle changing mechanism to change the shuttles in both boxes. 105
- 45 10. In a shuttle changing loom, the combination of the lay, two shuttle boxes at each side of the loom, two shuttle magazines at the replenishing side of the loom, shuttle carriers for conveying shuttles from the magazines to the two shuttle boxes, and means for operating the two shuttle carriers to transfer shuttles from the two magazines to the two shuttle boxes at the same time. 110
- 50 11. In a shuttle changing loom, the combination of the lay, two shuttle boxes at each side of the loom, two shuttle magazines at the replenishing side of the loom, mounted at different heights, shuttle carriers for conveying shuttles from the magazines to the two shuttle boxes, and means for operating the two shuttle carriers to transfer shuttles from the two magazines to the two shuttle boxes at the same time. 115
- 55 12. In a shuttle changing loom, the combination of the lay, two shuttle boxes at each side of the loom, two shuttle magazines at the replenishing side of the loom mounted at different heights and one forward of the other, shuttle carriers for conveying shuttles from the magazines to the two shuttle boxes, and means for operating the two shuttle carriers to transfer shuttles from the two magazines to the two shuttle boxes at the same time. 120
- 60 13. In a shuttle changing loom, the combination of the lay having two shuttle boxes at one side of the loom, two shuttle magazines for loaded shuttles at the same side of the loom and having their shuttle discharge openings at different heights, two shuttle carriers mounted for movement along different paths to transfer shuttles from the magazines to the two shuttle boxes, and means for simultaneously operating both carriers. 125
- 65 14. In a shuttle changing loom, the combination of the lay having two shuttle boxes at one side of the loom, two shuttle magazines for loaded shuttles at the same side of the loom and having their shuttle discharge openings at different heights, two shuttle carriers mounted for movement along different paths to transfer shuttles from the magazines to the two shuttle boxes, and means for simultaneously operating both carriers. 130

14. In a shuttle changing loom, the combination of the lay having two shuttle boxes at one side of the loom, two shuttle magazines for loaded shuttles at the same side of the loom, and having their shuttle discharge openings at different heights, two shuttle carriers mounted for swinging movement along different arcs to transfer shuttles from the magazines to the two shuttle boxes, and means for simultaneously operating both carriers. 70
15. In a shuttle changing loom, the combination of the lay, two shuttle boxes at each side of the loom, two magazines for loaded shuttles at the replenishing side of the loom, two feelers at the non-replenishing side of the loom, shuttle changing mechanism, and means controlled by each feeler for operating the shuttle changing mechanism to transfer a shuttle to each of the two shuttle boxes when either feeler detects substantial exhaustion of filling in either shuttle. 75
16. In a filling replenishing loom weaving with two shuttles, the combination of the lay having two replenishing shuttle boxes, shedding mechanism, filling replenishing mechanism for each shuttle, filling feelers for detecting the condition of the filling in the two shuttles, and mechanism controlled by the filling feelers to replenish both shuttles simultaneously when the filling feelers detect substantial exhaustion of filling in either shuttle. 80
17. In a shuttle changing loom, the combination of the lay provided with two shuttle boxes at one end, shuttle changing mechanism for simultaneously changing the shuttles in the two boxes, filling feeler mechanism for setting the shuttle changing mechanism in operation to change both shuttles when the filling feeler mechanism detects substantial exhaustion of filling in either shuttle, filling fork mechanism for stopping the loom upon the occurrence of a miss pick by either shuttle, and auxiliary means controlled by the filling fork mechanism for preventing operation of the shuttle changing mechanism when the filling fork mechanism detects a miss pick by either shuttle. 85
18. In a filling replenishing loom weaving with two shuttles, the combination of the lay having two replenishing shuttle boxes, replenishing mechanism for replenishing both shuttle boxes at the same time, filling feeler mechanism for initiating the operation of the replenishing mechanism, filling fork mechanism for detecting failure of filling to be laid in the shed by either shuttle, and auxiliary means controlled by the filling fork mechanism for preventing operation of the replenishing mechanism when filling fails to be laid by either shuttle. 90
19. In a filling replenishing loom weaving with two shuttles, the combination of the lay having two replenishing shuttle boxes, replenishing mechanism for replenishing both shuttle boxes at the same time, filling feeler mechanism for initiating the operation of the replenishing mechanism when the filling in either shuttle becomes substantially exhausted, filling fork mechanism for detecting failure of filling to be laid in the shed by either shuttle and thereupon effecting loom stoppage, and auxiliary means controlled by the filling fork mechanism for preventing operation of the replenishing mechanism when filling fails to be laid by either shuttle. 95
20. In a filling replenishing loom weaving with two shuttles, the combination of the lay having two replenishing shuttle boxes at one side of the loom, for replenishing the filling in both boxes on substantial exhaustion of filling in either shuttle, power means for restarting the loom on completion of filling replenishment in both boxes, and a safety mechanism for rendering the power means ineffectual to start the loom should either shuttle be improperly boxed. 100
21. In a filling replenishing loom weaving with two shuttles, the combination of a shipper, the lay having two replenishing shuttle boxes at one side of the loom, mechanism for stopping the loom and replenishing the filling in both boxes at the same time upon detection of substantial exhaustion of filling in either shuttle, power means including a starting rod detachably connected to the shipper for starting the loom, and means for disengaging the starting rod and shipper to prevent starting the loom by power should either shuttle be improperly boxed. 105
22. In a shuttle changing loom weaving with two shuttles, the combination of the lay having two replenishing shuttle boxes at the replenishing side of the loom, a single front wall for both replenishing boxes, two links pivotally connected to the single wall of the shuttle boxes, and means for operating said link to prevent the front wall of the shuttle boxes from swinging outwardly therefrom to any substantial extent as the wall is moved from and to its operative position. 110
- In testimony whereof, I have signed my name to this specification. 115
- ARTHUR S. COWAN.
